Primary Examiner — Eliza Z Harvey(74) *Attorney, Agent, or Firm* — FOLEY & LARDNER LLP(57) **CLAIM**

The ornamental design for a bed hook with adapter as shown and described.

DESCRIPTION

FIG. 1 is a top, rear, left perspective view of the claimed design, showing environmental structure;
FIG. 2 is a close up view of region 2 of FIG. 1;
FIG. 3 is a rear, left perspective view of FIG. 1, showing environmental structure;
FIG. 4 is a bottom, front, right perspective view of FIG. 1;
FIG. 5 is a top, rear, left perspective view thereof;
FIG. 6 is a front elevation view thereof;
FIG. 7 is a rear elevation view thereof;
FIG. 8 is a left elevation view thereof;
FIG. 9 is a right elevation view thereof;
FIG. 10 is a top plan view thereof; and,
FIG. 11 is a bottom plan view thereof.

The broken lines show portions of the bed hook with adapter and are for the purpose of illustrating environment and form no part of the claimed design. Any shade lines in the drawings show contour and not surface ornamentation.
